UNITED STATES PATENT OFFICE

2,573,983

TEMPERATURE FUSIBLE PLUG FOR
SPRAYING APPARATUS

Frank W. Ofeldt, Carnot, Pa., assignor to Homestead Valve Manufacturing Company, Coraopolis, Pa., a corporation of Pennsylvania

Application July 15, 1948, Serial No. 38,833

2 Claims. (Cl. 122—504.1)

1

This invention relates generally to temperature protective devices and more particularly to method and apparatus for thermally protecting the hose or heat sensitive device of spray generators and including fuse plugs for use with spray generating apparatus.

Spray generating apparatus is designed to supply metered quantities of liquid which is heated to produce a spray mixture of the liquid and the vapor of a liquid that is discharged through a hose and a nozzle in the form of a spray. By properly proportioning the liquid and the steam, or the liquid and fuel used to produce the spray mixture, a spraying apparatus may be made to operate within the latent heat range which provides flash vaporization at the nozzle resulting in a spray having a temperature of two hundred and twelve degrees F. at the nozzle opening. By properly designing the nozzle different types of sprays may be produced for various purposes such as a finely atomized spray for close cleaning and agricultural spraying of bushes, trees and ground crops or the spray may have a solid center for use in cleaning a surface several feet away.

Regardless of the character or type of generating apparatus, the nozzle employed, or the controls provided for maintaining proper operation of the spray generator, operators frequently allow the liquid supply to run low which causes air to be pumped with the remaining liquid. The proper metered quantity of liquid will of course not be supplied to the heating zone of the generator and the smaller quantity of liquid is converted into excess or superheated steam. Under such conditions the fuel supplied is metered for a materially greater quantity of liquid and thus overheats the liquid producing the steam. A flexible rubber hose is used to conduct the spray mixture to a gun where it is discharged and this hose cannot stand the high temperature of steam or superheated steam and will therefore be burned out.

The principal object of this invention is the provision of thermal protective method and apparatus wherein a temperature protective device will create a bypass for fluids of predetermined temperature to protect a hose or other heat sensitive device from destruction.

Another object is the provision of a thermal protective device which will create a fluid bypass for the discharge hose or for a heat sensitive device and provide a cooling of the hose or heat sensitive device.

Another object is the provision of a temperature fuse plug enabled to withstand operating temperatures of the spray generator and creat-

ing a bypass for fluids at a predetermined temperature.

Another object is the provision of selected metals which, when alloyed, provide a thermal fuse plug having a predetermined softening or melting temperature characteristic for a spray generator apparatus.

Another object is the provision of a thermal fuse plug nozzle for use with a hose or heat sensitive device and which is arranged to inspirate cooling fluid through the hose or heat sensitive device when it functions due to excessive heat.

Other objects and advantages appear in the following description and claims.

15. The accompanying drawings show for the purpose of exemplification, without limiting the invention or claims thereto, certain practical embodiments of the invention wherein:

Fig. 1 is a diagrammatic view of a spray generating apparatus employing this invention; and

Fig. 2 is a view in section of the bypass and fuse plug comprising this invention.

Referring to Fig. 1 of the drawings, I represents a liquid supply tank, the level of liquid

25 being controlled by the float 2 arranged to actuate the valve 3 which regulates the flow of liquid from the supply pipe 4. The liquid is withdrawn from the tank 1 through the pipe 5 by the reciprocating pump 6, the piston 7 of which is actuated by the crank 8 on the pulley 9 that is rotated by the motor 10 through the belt 11. The positive displacement pump 6 is provided with the inlet and outlet check valves 12 and 13, the latter passing the liquid supplied through the pipe 14 to the heating coil 15. The heated

35 liquid or spray mixture of liquid and vapor of a liquid passes from the coil 15 through the pipe 16 to the temperature protective device 17 from whence it flows laterally through the hose 18 and the nozzle 20 of the gun 21. Heat is supplied to the coil 15 by any suitable means such as the burner 22. The construction and operation of spray generating apparatus of this character may be found in United States Letters

40 Patents 2,289,674, July 14, 1942, Spray Generating Apparatus, and 2,128,263, August 30, 1938, Process and Apparatus for Heat Generation of Spray, wherein the liquid is supplied to the heat exchanger in metered quantities and the supply of fuel is correlated therewith to produce a mixture of liquid and vapor of a liquid.

The temperature protective device 17 is shown in Fig. 2 which comprises the T member 24 having the opposed aligned threaded openings 25 and 26 and the laterally connected smaller bore 55 27 which opens into the larger threaded bore

28 for receiving hose spud 30, which in turn has the nipple extension 31 for receiving the hose 18. A nipple 32 is secured in the threaded opening 25 which nipple is connected to the pipe 16 that conducts the heated spray mixture from the heating coils 15. The nipple 32 is provided with the bore 33 which is smaller in diameter than the bore of the opposed or fuse plug 34.

The threaded opening 26 is closed by the fuse plug 34 which consists of a short threaded nipple 35 having a non-round head 36 for tightening the same in the thread 26. The bore 37 of the nipple 35 is larger than the bore 33 and the former increases in diameter from the head 36 inwardly. This bore 37 is plugged by an alloy of lead and tin as indicated at 38. The alloy of lead and tin has a substantially constant softening point temperature of approximately one hundred and eighty-two degrees C. regardless of the relative percentage of lead and tin in an alloy within the limits of from ten to ninety percent by weight of lead to from ninety to ten percent by weight of tin.

The tapered plug 38 containing a solid solution of lead and tin will not melt or leak during the normal operation of the spray generator and it is maintained relatively cool by reason of the fact that it aids in dissipating heat from the liquid spray mixture. However, if the proportion of metered liquid falls below that required by the correlated amount of fuel supplied to the heat exchanger of the generator, the heated mixture will reach a temperature of one hundred and eighty-two degrees C. or greater in a very short time causing the plug 38 to soften or melt and blow out of the tapered bore 37. Since the tapered bore 37 is larger in diameter than the opposite bore 33 of the T fitting, it functions as an ejector causing air to be inspirated back through the nozzle 20, the hose 18, the nipple 30, the small bore 27, which air is discharged through the nipple 34 with the highly heated mixture. Thus the heated mixture bypasses the hose and cool air is drawn back through the hose to reduce its temperature. The 45 hose will stand the temperatures of the solution below that which is necessary to melt the plug 38 of the solid solution of lead and tin. It has been found preferable to construct the safety device 17 with the bore 33 smaller in diameter than the tapered bore 37 and the bore 27 smaller than the bore 33. These requirements provide proper inspirating or ejector characteristics for drawing air back through the hose and prevent its being burned out due to excessive temperatures of the spray mixture.

I claim:

1. A device for protecting a discharge hose of a spray generator by cooling comprising a T-fitting with two opposed openings and one lateral opening, said lateral opening being smaller than the other openings, said lateral opening being connected to a discharge hose and a pipe connecting one of said opposed openings to the generator to conduct the normal flow of heated spray solution from the generator through the fitting and the discharge hose, a nipple in the other of said opposed openings with a larger inside diameter than the pipe making the generator connection, and a fusible plug stopping said nipple but adapted to melt and flow out at a predetermined temperature to directly discharge the spray solution and inspirate air back through the hose and said lateral opening.

2. A thermal safety device for conducting heated fluids consisting of a T-fitting having two aligned openings and one lateral opening, the lateral opening being smaller than the aligned openings, a plug closing one of the aligned openings, said plug characterized by having predetermined softening and melting characteristics, and means to connect a source of heated fluid to normally flow into said other aligned opening and discharge out said lateral opening, excessively heated fluid melting said plug to discharge directly through the aligned openings and inspirate air through the smaller lateral opening and discharge it with the fluid out of said one aligned opening.
